UNITED STATES PATENT OFFICE.

FREDERICK BEDFORD, OF STRATTON, NEBRASKA, ASSIGNOR TO BEDFORD HEADLIGHT COMPANY, OF STRATTON, NEBRASKA, AN ASSOCIATION.

HEADLIGHT.

Application filed July 13, 1923. Serial No. 651,209.

To all whom it may concern:

Be it known that I, FREDERICK BEDFORD, a citizen of the United States, residing at Stratton, in the county of Hitchcock and

5 State of Nebraska, have invented certain new and useful Improvements in Headlights, of which the following is a specification.

10 The present invention relates to improvements in headlights, more particularly for use on automobiles and has for an object the provision of a construction in which suitable brilliance will be afforded to illuminate adequately the roadway, without 15 involving the objectionable glare of headlights and the blinding of motorists coming toward the lights.

Another object of the invention is to provide a lens in which the light rays normally 20 horizontal or directed downwards will be given passage without interference but wherein those rays reflected upwards will be absorbed and cut off.

25 A further object of the invention consists in securing the above-described results in simple, inexpensive and compact construction such as will conform to the standard structure of vehicle lamps and may be substituted for the lenses thereof.

30 With the foregoing and other objects in view, the invention will be more fully described hereinafter, and will be more particularly pointed out in the claims appended hereto.

35 In the drawings, wherein like symbols refer to like or corresponding parts throughout the several views,

Figure 1 is a longitudinal section taken vertically along the medial line of Figure 2.

40 Figure 2 is a front elevation or face, the glass 14 being removed.

Figure 3 is a plan view of a fin or sanded member.

45 Figure 4 is a plan view of a number of incised lower fins.

Figure 5 is a section of a fin.

Figure 6 is a longitudinal section of a modification of the device.

50 Figure 7 is a plan view of a modified fin.

Figures 8 and 9 are sectional views of modifications of fin constructions.

55 In the drawings the numeral 10 indicates a metal shell or housing 11 a reflector of polished silver plated metal, which is substantially semiglobular in shape, provided

with an electric light bulb 12 adapted to be connected with a battery (not shown).

The parts are well known in present lamp construction and additionally a metal ring 13 is usually provided with which to secure 60 the glass or lens in place. However no glass or lens, at least of the usual character is employed in the present case and the ring 13 subserves the function of holding the glass bulb or globe 14 and the glare shield 65 member as now described.

In Figure 1 a semi-globular glass 14 is employed, for the purpose of preventing the elements from entering the headlight.

70 The new device or shield is semi-globular in contour and consists of a metal ring 15 having a flange 16 adapted to be secured by the locking ring 13. The upper portion of the ring 15 may have a cap 17 thus forming a pocket 18. The fins above the bulb 12 or above the center are in horizontal alignment and any required number may be employed such as the fins numbered 19. The fin 20 may be at a slight tangent angle to the horizontal.

75 The fins 19 and 20 are semi-circular in plan as shown in Figure 3 and are soldered or otherwise suitably secured to the ring 15. These fins are treated as follows: In Figure 5 a section is shown. The numeral 21 indicates a shellac coating on the fins which are first dipped into a bath of this material and then dusted with sand 22 for purposes later described.

80 The lower fins need not be so treated unless a uniform appearance is desired and these fins, numbered 23 to 27, are segmental in plan as shown in Figure 4. Such fins are mounted on the ring 15 in a manner so that, preferably, they radiate from the light bulb 12 as a common center, or fanwise. The fins are provided with elongated slots 28 through which beams of light are adapted to be projected as later explained.

85 The fin 25 or the other may have one or more slots 28. Any number of fins may be employed according to the size and diameter of the headlight and according to how fine a division of the space is required.

90 In Figure 6 is shown a modification. The ring 15 is wider and provided with an extension fastening ring 13' for securing the flat glass 14'. The fins 19' are rectangular in plan as shown in Figure 7 and coated with sand 22. The ends 29 are beveled 105

110

for accurate fitting and soldering to the ring 15 which may also be coated with sand 22 if desired as shown near the top of Figure 6.

The lower fins 27', 26', 25', 24' and 23' 5 are similar to Figure 1 except that they are rectangular in plan. Any desired number may be employed having slots 28'.

Figure 8 shows a modification of the fin. Indicated at 30 are a large number of 10 irregular lumps or projections, formed in the metal fins by molding or pressing. These lumps 30 have the same function as the sand as later described.

Figure 9 is the same except that the lumps 15 31 are regular or corrugations, crimped into the metal in a uniform manner by rolling the metal through a die.

The construction shown in Figure 1 operates in the same manner as that shown in 20 Figure 6 and therefore but Figure 6 will be described.

In Figure 5 the numeral 32 indicates a 25 ray of light which is projected against the fin 19 at a tangent angle, where it strikes the grain of sand 22' which functions as a stop, bar or detent in a manner to absorb or obstruct, the further reflection of the ray as indicated by the dotted line 33. If any 30 of the light is not "killed" at 22' but is deflected upward as at 33, such ray of light will be of course weaker.

The irregular indentations projections, lumps or the like as shown in Figure 8 at 35 30 serve the same purpose. Also the regular wave-like corrugations 31 (Figure 9) do the same, but not as well.

In Figure 6 the ray of light 34 starts from the bulb 12 and is deflected and reflected at 35 to the fin at 36 where it is partly or 40 wholly "killed" or again deflected to 37 where it is totally minimized in a manner so that it will not project as at 38, at an upward angle to strike and blind an approaching driver.

A ray such as 39 may pass the fins, at a 45 horizontal with the ground. Such ray will not project upwardly.

Direct rays such as 40 may pass the lower fin but will be directed to the ground. A

ray such as 41 may pass through the elongated slots of the lower fins and do useful work. A ray 42 or 43 will be trapped and prevented from an upward slant, and be projected to the ground in front of the automobile for useful work.

I do not wish to be restricted to the size, form, and proportions of the various parts, and obviously changes could be made in the construction herein described without departing from the spirit of the invention, it being only necessary that such changes fall within the scope of the appended claims.

What is claimed is:—

1. A device as described comprising a 65 light source, a reflector, a series of spaced apart substantially horizontal fins disposed in front of the upper portion of the reflector and having corrugated surfaces, and a second series of fins disposed in front of the 70 lower portion of the reflector and being inclined from the reflector downwardly and outwardly, certain of said inclined fins having single slots therein and certain other of the inclined fins having a plurality of slots 75 therein.

2. A device as described comprising a light source, a reflector associated therewith, a ring extending about the edge of the reflector, means to hold the ring in place, a hood carried by the upper end of said ring, a plurality of fins secured to said ring and extending thereacross in a substantially horizontal direction, said fins being spaced apart and being elongated in the direction 80 of the path of the light rays, said fins being provided with light-absorbent surfaces, certain of said fins being inclined and provided with slots, the slots in one fin adapted to register into substantially horizontal direction with the slots of adjacent fins.

In testimony whereof, I have affixed my signature in presence of two witnesses.

FREDERICK BEDFORD.

Witnesses:

WADE R. MARTIN,
HIRAM A. STURGES.
